PELLET IMPLANTER

Henry R. Eisenhand, Denver, Colo., assignor to American Home Products Corporation, New York, N.Y., a corporation of Delaware

Filed June 8, 1966, Ser. No. 2,600

Term of patent 14 years

(Cl. D83—12)

FIG.1.

FIG.2.

FIG.3.

FIG. 5.

FIG. 4.

FIG. 6.

FIG. 1 is a top plan view of a pellet implanter, showing my new design;

FIG. 2 is a side elevation thereof;

FIG. 3 is a bottom plan view thereof;

FIG. 4 is a side elevation opposite that shown in FIG. 2;

FIG. 5 is a front plan view thereof;

FIG. 6 is a rear plan view thereof.

I claim:

The ornamental design for a pellet implanter, as shown.
